CLAIM

The ornamental design for a handheld fish scale as shown and described.

DESCRIPTION

FIG. 1 is a front view of the handheld fish scale;
FIG. 2 is a rear view of the handheld fish scale of FIG. 1;
FIG. 3 is a left side view of the handheld fish scale of FIG. 1;
FIG. 4 is a right side view of the handheld fish scale of FIG. 1;
FIG. 5 is a bottom view of the handheld fish scale of FIG. 1;
FIG. 6 is a top view of the handheld fish scale of FIG. 1;
FIG. 7 is a front, bottom and left side perspective view of the handheld fish scale of FIG. 1;
FIG. 8 is a front, bottom and right side perspective view of the handheld fish scale of FIG. 1;
FIG. 9 is a front, top and right side perspective view of the handheld fish scale of FIG. 1;
FIG. 10 is a front, top and left side perspective view of the handheld fish scale of FIG. 1;
FIG. 11 is a rear, top and right side perspective view of the handheld fish scale of FIG. 1;
FIG. 12 is a rear, top and left side perspective view of the handheld fish scale of FIG. 1;
FIG. 13 is a rear, bottom and left side perspective view of the handheld fish scale of FIG. 1; and,
FIG. 14 is a rear, bottom and right side perspective view of the handheld fish scale of FIG. 1.
The broken lines shown in the Figures represent portions of the handheld fish scale that form no part of the claimed design.
